UNITED STATES PATENT OFFICE.

CHARLES C. McCCLAIN, OF AKRON, OHIO.

WEDGE FOR TOOL-HANDLES.

1,203,025.

Specification of Letters Patent. Patented Oct. 31, 1916.

Application filed November 28, 1914. Serial No. 874,399.

To all whom it may concern:

Be it known that I, CHARLES C. McCCLAIN, a citizen of the United States, residing at Akron, in the county of Summit and State 5 of Ohio, have invented certain new and useful Improvements in Wedges for Tool-Handles, of which the following is a specification.

This invention relates to wedges for tool handles and it has for its object the provision of a device of this character constructed 10 in such manner as to split and separate the wood of the handle and expand the same within the eye of the tool, said wedge being provided with prongs adapted to engage the 15 metal of the inner wall of the eye of the tool whereby said wedge is held against displacement.

It is a further object of the invention to provide a wedge of the type set forth, comprising a pair of complementary members, one of which splits the wood of the handle in one direction and the other of which lies at right angles thereto and splits the wood of the handle in the opposite direction, each of 20 said members being provided with yieldable spurs or prongs adapted to engage the metal constituting the wall of the eye of the tool.

Further objects and advantages of the invention will be set forth in the detailed description which now follows:

In the accompanying drawing, Figure 1 is a perspective view illustrating the complementary members of the wedge in assembled position and Fig. 2 is a vertical sectional view illustrating the wedge applied to a tool of the hatchet type.

Like numerals designate corresponding parts in both of the figures of the drawings.

Referring to the drawing it will be seen 40 that the invention comprises a pair of wedges A and B. The wedge A is provided with a central opening 5 from which a slot 6 extends to the upper face of the wedge so that the portions of the wedge upon the opposite 45 sides of this slot are rendered more or less yieldable toward and from each other. This slot also forms a passage for the reception of wedge B as hereinafter described. Openings 7 are formed through the wedge and prongs 50 8 extend outwardly from the outer sides of these openings whereby said prongs are rendered to a certain extent yieldable. The portions 9 of the wedge are flattened upon their upper faces and these portions 9 constitute 55 driving elements by which the wedge may be driven into position. In like manner the

wedge B is provided with the central opening 5^a, vertical slot 6^a, prongs 8^a and driving members 9^a. The wedge B is materially smaller than wedge A and is adapted when driven into position to lie at right angles to the wedge A and within the slot 6. This wedge B is of such thickness that it spreads the upper part of the wedge A apart so that when the two wedges are driven into the position shown in Fig. 2, wedge A lies lengthwise of the eye of the tool and its prongs 8 engage and stick into the wall of the tool as illustrated at 8^b. In like manner the prongs 8^a of the wedge B engage and stick into the 70 wall of the tool.

From the foregoing description it will be seen that there is herein provided a very simple and inexpensive wedge for tool handles, one that may be readily stamped out and one 75 that will be securely held against accidental dislodgment after being driven into position.

While the elements shown and described are well adapted to serve the purposes set forth, it is to be understood that the invention is not limited to the precise construction shown but that it includes within its purview such changes as may be made within the scope of the appended claims.

Having described my invention what I 85 claim is:

1. A wedge for tool handles comprising a body portion having prongs at its upper outer corners, said wedge being of such length as to span the eye of the tool and 90 cause said prongs to engage the metal of the eye of the tool.

2. A wedge for tool handles comprising a body portion having a sharpened lower edge, a driving portion at its upper edge and outwardly directed prongs at its upper outer corners, said prongs being spaced from said driving portion to render them yielding and said prongs acting to bite into the metal of the eye of the tool.

3. In a device of the character described, a pair of wedges one of which is transversely slotted to permit the other of said wedges to lie within said slotted portions and at right angles to the first named wedge each of said wedges having prongs formed at its upper outer corners and each of said wedges being of such length as to span the eye of the tool and cause their upper outer corners to bite into the metal of the eye of the tool.

4. In a device of the character described, a pair of wedges each of said wedges being

vertically and centrally slotted, driving portions having flat upper faces upon each side of the central slot and resilient prongs lying outwardly of said driving portions and forming the upper outer corners of said wedges, said wedges being of such length as to span the eye of the tool and bite into the metal of the eye of the tool.

5. In a device of the character described, a pair of wedges each of said wedges being transversely pierced adjacent its lower edge and vertically slotted from said pierced portion to its upper edge, driving portions formed upon each side of said slot, and resilient prongs lying outwardly of said driving portions and constituting the upper corners of the wedge, said wedges being of such length as to span the eye of the tool and cause their upper outer edges to bite into 20 the metal of the eye of the tool.

6. In a device of the character described, a wedge comprising a body portion having a sharpened lower edge and outwardly directed prongs at its upper outer corners, said wedge being vertically slotted from its upper edge and a second wedge adapted to lie at 25 right angles to the first named wedge and within the slotted portion thereof said sec-

ond wedge being of such thickness as to spread the portions of the first named wedge apart.

7. In a device of the character described, a pair of wedges, each of said wedges being transversely pierced adjacent its lower edge and vertically slotted from said pierced portion to its upper edge, driving portions formed upon each side of said slot, inclined slots at the outer side of said driving portion to thereby form resilient prongs lying outwardly of said driving portions, one of 40 said wedges being smaller than the other and said smaller wedge lying in the first named vertical slot of the larger wedge and of such thickness as to spread the upper portion of said larger wedge apart when said smaller wedge is driven into position, said wedges being of such length as to span the eye of the tool and cause their resilient prongs to bite into the metal of the eye of the tool.

50 In testimony whereof I affix my signature in presence of two witnesses.

CHARLES C. McCALAIN.
